Primary Examiner—Robin V Webster*Assistant Examiner*—Linda Brooks(74) *Attorney, Agent, or Firm*—Kenyon & Kenyon LLP(57) **CLAIM**

The ornamental design for a bicycle parking assembly, as shown and described.

DESCRIPTION

FIG. 1 is a front perspective view of a bicycle parking assembly showing my new design.

FIG. 2 is a front view thereof.

FIG. 3 is a left side view thereof.

FIG. 4 is a top view thereof.

FIG. 5 is a right side view thereof; and,

FIG. 6 is a back view thereof.
